[57] ABSTRACT

A raisin grape spreader has a carriage movable over the ground and supports a roll of paper fed from the roll at controlled rates relative to the carriage advance and laid as a strip on the ground under raisin grapes from a hopper on the carriage deposited by a feeding conveyor. Guides on the carriage temporarily lift the paper strip edges as the carriage advances, and a knife severs the strip at the end of a deposit operation.

RAISIN GRAPE SPREADER

It is becoming increasingly necessary to provide means for mechanizing the handling of raisin grapes for the manufacture of raisins and generally to improve the raisin making technique. At present raisin grapes are largely hand picked and laid out by hand on rectangular paper trays for sun drying in the vineyard. The grapes are subject to other hand operations, such as rearranging and turning, and when dried are taken from the trays, usually by hand. The used trays are taken from the vineyard and destroyed, being replaced for subsequent use. This is essentially a batch or unit process and is not easily mechanized.

We have experimented to determine whether or not it is feasible to lay a ground cover such as paper between the vine rows in a vineyard and deposit raisin grapes thereon for drying, the deposit being as uniform as possible and in a relatively thin layer, so that the grapes, without turning, are uniformly dried into raisins. This technique has proved to be successful under the test conditions.

It is therefore an object of our invention to provide a machine which will lay a strip of paper continuously on the ground, preferably in the aisle between the rows of vines in a vineyard, and which will also deposit uniformly a layer of raisin grapes on the paper strip for drying.

Another object of the invention is to provide a raisin grape spreader that will easily start the laying of a paper strip in position at the beginning of a row and will terminate the laying easily at the end of a row.

A further object of the invention is to provide easy and convenient ways of depositing a strip of paper in a vineyard, for example, by a machine which utilizes a small amount of only modestly skilled labor.

Another object of the invention is to provide a raisin grape spreader that is effective to confine the deposited grapes substantially within the bounds of a paper strip and which avoids contaminating the laid grapes with surrounding earth, debris or other undesired material.

A further object of the invention is to provide a raisin grape spreader that affords a relatively level, uniformly deep and constant width band of deposited grapes on a ground cover such as a paper strip.

A further object of the invention is in general to provide an improved raisin grape spreader.

Other objects together with the foregoing are attained in the embodiment of the invention described in the accompanying description and illustrated in the accompanying drawings, in which:

FIG. 1 is a diagrammatic view, largely in side elevation with one side of the machine removed, showing the general organization of the raisin grape spreader of the invention;

FIG. 2 is a cross-section to an enlarged scale, the plane of section being indicated by the lines 2—2 of FIG. 1;

FIG. 3 is a detail showing in plan a portion of the structure enlarged in FIG. 2, the direction of the view being indicated by the line 3—3 of FIG. 2;

FIG. 4 is a cross-section to an enlarged scale, the plane of section being indicated by the line 4—4 of FIG. 1;

FIG. 5 is a side elevation showing diagrammatically the principal parts of a modified form of raisin grape spreader, the frame and other unmodified structures being omitted for clarity;

FIG. 6 is a cross-section, the plane of which is indicated by the line 6—6 of FIG. 5;

FIG. 7 is a side elevation of a modified form of a paper handling mechanism for use with the remainder 5 of the raisin grape spreader, as shown herein; and

FIG. 8 is a half plan of the modified structure of FIG. 7.

A device related to the presently disclosed raisin grape spreader is shown in U.S. Pat. No. 3,587,931 issued June 28, 1971 and in our copending application entitled "Raisin Pick Up Machine" filed on Dec. 10, 1971 with Ser. No. 206,600. Some of the description and terminology used in that instance apply to this device.

15 In a preferred form as disclosed herein, the raisin grape spreader pursuant to the invention preferably includes a carriage, generally designated 6, of a size and character adapted readily to advance in the direction of the arrow A along the aisle between the rows of grape vines in a vineyard, for example. The carriage has a main frame 7 at its forward end supported on dirigible wheels 8 and at its rearward end supported on driving wheels 9 all running on the ground 10. The rear wheels 9 are arranged on an axle 11 carrying one or more hydraulic propulsion motors 12, as desired. These are supplied with pressure hydraulic fluid from a hydraulic mechanism 13, diagrammatically illustrated, and including the usual pump, relief valve, control valves, and the like, all driven by an internal combustion engine 14, also diagrammatically illustrated, and mounted on the frame 7.

30 Adjacent the rear end of the frame is an operator's station 16 from which the operation can control a hydraulic regulating valve 17 controlling the supply of hydraulic fluid to the motor 12 and governing the rate of advance of the carriage in the field. It is customary to propel the carriage at a reasonably uniform rate consistent with variations in the job conditions. The operator 35 likewise has a steering mechanism 18 available to maneuver the wheels 8. The machine can be guided along the rows, which are usually straight, but also can follow the curvature of rows that happen to be of a different configuration, and can easily and sharply be turned at 40 the end of a row ready to start into an adjacent row.

45 Particularly in accordance with the invention, there is provided at the forward or leading end of the frame 7 a pair of supports 21 and 22 for supporting a roll 23 of paper, illustrative of materials which may be laid on the ground. Such materials may be in the form of separate sheets or in the form of a continuous strip so long as they act to support the raisin grapes as they are drying. While it is entirely possible to utilize sheets and to use different kinds of material rather than a strip or band of paper, a paper strip in a roll configuration has proved appropriate in present use. The roll 23 of paper is of a width which is a substantial portion of the distance between the rows of grape vines and is confined in a transversely centered location on the frame 7 by means of end flanges 24 on the support 22. While both of the supports 21 and 22 may be free-turning rollers and freely support the roll 23, it is preferred to block the support 22, leaving the roller 23 free. There is some friction against the support 22 serving as a drag on the paper roll. The paper roll can easily be placed on and removed from the support without dismantling any machinery.

Paper is pulled from the roll 23 under some tension and is led on a path 26 extending between a pair of feeding rollers 27 and 28. Each roller is journaled on its respective one of a pair of cross shafts 29 and 31 rotatably mounted in a stand 32 supported on the frame 7. The roller 28 is free to lower by gravity toward the roller 27 so that the rollers 27 and 28 grip the paper from the roll 23 between them for feeding purposes. The roller 27 is preferably rubber covered and is connected by a belt 33 to a drive pulley 34 on a hydraulic motor 36. Supply and return lines 37 and 38 extend to the hydraulic unit 13. The supply line 37 is joined through a hand valve 39 to the return or exhaust line from the vehicle driving motor 12. By working a handle 41 of the valve 39 the vehicle operator can direct the discharge from the motor 12 to the hydraulic unit 13 or can connect the motors 12 and 36 in series so that the paper strip feed is related to the vehicle advance. It is sometimes desired to have the paper fed through the rollers 27 and 28 faster than the motor 36 may then be set to run. There is consequently incorporated in the drive between the hydraulic motor 36 and the pulley 34 an overrunning clutch mechanism 43 permitting the pulley 34 and the roller 27, when so impelled, to rotate faster than the hydraulic drive motor 36.

Upon emerging from between the rollers 27 and 28, the paper strip moves under a guide bar 44 mounted on supports 46 on a cross shaft 47 journaled with respect to the frame 7 and manually positioned by the operator. Normally the guide bar 44 is located as shown in FIG. 1, so that as the feed rollers advance the paper strip, the paper is guided to lie on the ground 10 beneath the carriage.

About centrally mounted on the frame 7 is an open top hopper 51 of substantially the free-flowing, non-jamming shape shown. The hopper receives raisin grapes from any suitable source, such as a harvesting machine travelling along the same grape row with or alongside the carriage 6 or travelling in an adjacent row. The harvesting machine can even be combined with the spreader in one unit. The hopper 51 contains raisin grapes discharging therefrom through a transverse orifice 52 located at the lower portion of the hopper and extending for substantially the same width as the paper.

Disposed on the frame 7 beneath the outlet 52 of the hopper is a feeding mechanism including a belt 53 trained around an idler roller 54 and a driven roller 56 both journaled on the frame 7. The roller 56 is driven by a belt 57 from a hydraulic motor 58. A manually actuated motor control valve 62 is provided on the hydraulic unit 13. The operator by properly manipulating the valve 62 can control the rate of operation of the motor 58, and so the rate of operation of the feed belt 53. The upper run of the belt 53 moves opposite to the direction of advance of the carriage 6, or rearwardly.

In some installations, the feed belt 53 has its upper run moving forwardly to discharge over the front end. This is entirely feasible but in this case the hopper 51 is usually mounted to discharge forwardly, also. Grapes either in clusters or as single berries from the hopper 51 are carried away from the opening 52 to permit the egress of additional raisin grapes. The speed of motion of the belt 53 governs the rate of removal of the raisin grapes from the hopper and so governs the rate at which the raisin grapes round the rearward roller 54 and fall onto the subjacent paper strip. The rate of de-

posit of the raisin grapes is coordinated with the rate of advance of the machine, i.e. the rate of laying of the paper strip by the series interconnection of the motors 12 and 36 and the drive ration to the roller 31. A relatively uniform layer of raisin grapes is thus laid down. Since the feeding device and the paper strip are approximately the same width, the full width of the strip, nearly, is laden with raisin grapes.

We have particularly found that it is of great assistance in ensuring that the individual grape berries or bunches are confined to the paper and that any surrounding debris or earth is kept from the deposited grapes if the edges of the paper strip are turned up. Further, we have found that it is not necessary to make this turn-up into a permanent feature of the paper strip, but only in the area and during the time that the grapes are being deposited. Upon deposit the individual grapes and bunches quickly become stable and stay in position if they are initially confined. For that reason, there are 15 provided on the frame 7 at each side thereof identical devices in the nature of means for temporarily lifting the paper edges.

On cross pins 66 journaled in the frame sides there are mounted levers 67 joined by a cross bar 68 manually positionable by the operator. Each lever 67 carries a sleeve 69 within which a rod 71 is rotatable. The lower end of each rod is bent to occupy a position inwardly of the paper edges and slightly rearwardly of the rod shank. Rotation of the rod too far rearwardly is precluded by a stop 72 on the rod which engages a shoulder 73 on the surrounding sleeve 69.

In the ordinary transport of the machine, the levers 67 are actuated by the cross bar 68 so that the rods are lifted considerably above the ground and have no particular effect. However, when the paper strip is being dispensed and shortly before grape deposit commences, the levers 67 are moved into the position shown in FIG. 1 by lowering the bar 68. The lower ends of the rods 71 are brought into light engagement with the ground 10. Advance of the frame 7 over the ground makes the bent ends of the lowered rods rotate inwardly of the frame and rearwardly until the stops 72 are effective to preclude further rearward motion. In this extreme position the bent ends of the rods extend 20 transversely or slightly rearwardly of a transverse location.

As the machine advances, the dispensed paper rises or is lifted from the ground over the curvature of the lower ends of the rods so that the strip edges are temporarily curled up and lifted. The natural stiffness of the paper causes this curvature to extend forwardly and rearwardly of the bent rod ends so that there are upturned margins formed on the strip as it is being laid, particularly in the portions of the strip immediately 25 below the dispensing or feeding belt 53. As the grapes are deposited they are put into what is in effect a temporary trough. When the grapes have reached the ground, have stopped rolling or tumbling about and are stable, the paper has passed beyond and to the rear of the inturned lower ends of the rods 71 and resumes a flat condition. The upturned edges of the paper lower onto the ground easily and overlie any clods or debris or other irregularities.

In operating the machine at the beginning of a row, it is headed in the direction of the arrow A down the aisle. The operator starts the carriage forwardly and starts the feed of the paper by energizing the hydraulic

motors 12 and 36. The operating rolls 27 and 28 unreel the paper gripped between them. The paper falls onto the ground below and to the rear of the guide bar 44. The operator controls the rate of advance of the carriage 6 by regulating the hydraulic motor 12. Preferably the paper is dispensed onto the ground at a linear speed somewhat less than the linear rate of advance of the carriage. This means that in entering the aisle between the rows the first part of the paper strip initially drags along the ground at a relatively slow rate. As the initial raisin grapes are deposited from the feeding mechanism onto the paper, the weight of the deposited grapes is soon sufficient to hold the paper on the ground and stop its forward advance. As the machine advances the paper from the roll 23 drawn between the rolls 27 and 28 as required by the speed of advance of the carriage and faster than the motor 36 causes the paper to be fed by the rolls. This means that the paper is tensioned and the over-running clutch 43 is active. Under these conditions the motor 36 can be de-energized, if desired.

As the machine approaches the end of a row, the grape discharge is stopped and the paper is severed. This is done by rotating the guide bar 44 from its guide position and advancing a cutting knife 76 also mounted on the cross shaft 47 and supports 46. Preferably the knife is of a serrated nature and is plunged into the web of paper being dispensed. The paper is completely or partially severed so that it tears off of the roll, leaving the deposited end flat on the ground. The retained portion is in position to start the dispensing again upon energization of the motor 36 at the beginning of the next aisle and a repetition of the starting sequence.

If the ground between the vine rows is relatively smooth and level, it is not necessary that it be treated in any fashion before the paper is laid on it. Under some circumstances, however, the ground is not particularly level or smooth, and hence we provide a relatively heavy roller 77 on a cross axle 78 mounted in a frame 79 connected to the frame 7 by a pivot shaft 81. If the roller 77 is not needed, and during general transport of the vehicle, the roller 77 can be lifted from the ground. However, if rough ground conditions are encountered, the roller 77 is lowered and serves not only to crush or displace small clods but tends to level the ground and to smooth it so that an appropriate bed is provided for the reception of the paper strip.

Sometimes and for various reasons the receipt of grapes by the hopper 51 is irregular and, despite some evening-out of the variations by reason of the capacity of the hopper, the distribution of the grapes onto the paper strip is not as uniform as is desired. For that reason, the device may be modified to include a distribution structure such as a storage belt between the hopper and the feed belt.

As shown in diagrammatic FIGS. 5 and 6, the main portions of the machine remain as previously disclosed but some alterations and additions are made. The frame 7 is carried on front wheels 8 and rear wheels 9 and has a paper roll 23 fed between feeding rollers 27 and 28 and under a guide bar 44 and deposited on the ground 10. A feeding belt 53 is driven by a motor 58 and discharges rearwardly onto the subjacent paper strip disposed in the path 26.

The grapes, as before, are received from a conveyor 89 and are deposited in a special hopper 91. As especially shown in FIG. 6, the hopper has a funnel-like,

downwardly converging top section 92 leading through a throat 93 to a downwardly diverging bottom section 94. The angle of divergence of the side walls of the bottom section is slightly steeper than the natural angle of repose of the received grapes. The contained grapes therefore rest on a regulating conveyor 96 without deleterious contact with the side walls.

The conveyor 96 is a belt trained over supporting rollers 97 and 98 on the frame 7 and is driven by a motor 99 with its top run moving toward the trailing end of the vehicle. The grapes are transported by the conveyor 96 through a discharge opening 101 from the hopper 91 into a guide chute 102. They fall there-through onto the feeding belt 53 and then are carried onto the paper below, being laterally confined by side boards 103. The motor 99 is under variable speed control by the operator. The speed of the belt 96 is thus regulated to speed up or delay the transit of grapes from the hopper to the belt 53 so that, despite variable grape receipt, the supply to and discharge from the belt 53 is smoothed out and made as nearly uniform as possible.

To prepare the ground, the usual roller 77 is preceded by a drag 104 flexibly trailing from the axle of the front wheels 8.

In some areas and at some times the raisin grapes spread for drying are subject to rainfall. It is desirable to shed and dispel the rain water as promptly and effectively as possible. To accomplish this, some modifications in and additions to the previously described machines are made as shown in FIGS. 7 and 8.

As before, the parts are the same unless particularly changed. The main frame 7 at the forward end is carried on wheels 8. Above the wheels are uprights 106 having notches 107 at the upper end to support, with some frictional drag, a shaft 108 carrying a paper roll 23. The paper extends on a path 26 to the feeding rollers 27 and 28, the former being driven by the motor 36, as before.

In this hemisphere the grapes for drying are disposed in east-west rows, the rows being located as well as possible to get exposure to sun from the south. To contend with rainfall, it is preferred to prepare the ground 10 between the grapevine rows to have a slope toward the south. This is usually done by advance grading. In addition, the roller 77 is mounted on the frame 7 at a similar slope and is preceded by a drag 109 in the form of a rail or bar or in the form of a drum fastened against rotation in a yoke 111 connected to the axle of the front wheels 8 by a chain 112. In this fashion, the sloped ground is preliminarily smoothed.

To assist in retaining the deposited grapes on the inclined paper yet to facilitate rain water runoff, the paper strip is specially treated. After leaving the roll 23 and on the way to the feeding rollers 27 and 28, the paper passes over a supporting table 116 disposed at an inclination on the frame 7. At the leading end of the table and on one or preferably both sides thereof are located piercing dies 117 and 118. These are narrow wheels having alternating teeth and flats that are intermeshed and slightly spaced apart. They are driven by a belt 119 extending from the axle of the driven roller 27. Thus, as the paper advances it is provided near and parallel to one or both edges with a line of spaced perforations. Sometimes such perforated paper is available from the mill and the piercing dies 117 and 118 can then be omitted.

The paper perforated near the edge in advancing over the table 116 encounters edge-folding dies 121. These are mounted on the table 116 to swing out of the way if not needed or to overlie the table and the paper edge. The dies 121 are somewhat helically shaped and engage under the edge of the advancing paper. They lift up the paper edge, fold it, usually along the line of the perforations, and release it so that the advancing paper emerges from the dies with folded, marginal flanges along one or both edges.

The so-folded paper passes between the feeding rolls 27 and 28 and under the guide bar 44. The paper may have sufficient resiliency so that the flange or flanges, temporarily flattened, partially reerect themselves. They are assisted in this by opening cams 122 on brackets 123 depending from the frame 7 and which engage between the flanges and the main body of the paper and pry the flanges into a position about normal to the general plane of the paper. There results a south sloping trough having perforations at least along the south flange fold where it joins the main sheet.

With this arrangement rain tends to run off toward the south and to escape from the paper strip onto the ground through the various perforations. Subsequently, when the raisins are picked up, the paper, in being pulled up between lifting rolls, tends to flatten into its original cross-sectional contour, eliminating the flanges and leaving a smooth sheet from which to remove the raisins.

What is claimed is:

1. A raisin grape spreader comprising a carriage adapted to be advanced over the ground, means for advancing said carriage over the ground at a predetermined rate, means for supporting a supply of paper on said carriage, means independent of said carriage advancing means for feeding paper from said supply at a controlled rate differing from said predetermined rate onto the ground under said carriage, means on said carriage for containing raisin grapes, and means on said carriage for feeding raisin grapes from said containing means onto said paper on the ground.

2. A device as in claim 1 including means under operator control for regulating said paper feeding means.

3. A device as in claim 1 including an overrunning drive in said paper feeding means effective to permit paper to be drawn from said supply faster than said paper is dispensed from said supply by said paper feeding means.

4. A device as in claim 1 including means for advancing said carriage over the ground at a predetermined rate and for regulating said feeding means to feed paper onto the ground at a lesser rate.

5. A device as in claim 1 including means for severing said paper at a location on said paper spaced from and situated between said feeding means and the ground.

6. A device as in claim 1 including means for temporarily lifting and dropping the edges of said paper in the vicinity of the area thereof on which said raisin grapes are deposited by said feeding means.

7. A device as in claim 6 in which said lifting means are guide fingers depending from said carriage and extending under the edges of said paper.

8. A device as in claim 6 in which said guide fingers are retractable laterally from a position under the paper to a position alongside the paper.
